UNITED STATES PATENT OFFICE.

CHARLES P. MONASH, OF CHICAGO, ILLINOIS.

DESIGN FOR A SUPPORT FOR A STATUE.

No. 39,769.

Specification for Design.

Patented Jan. 12, 1909.

Application filed October 21, 1908. Serial No. 458,913. Term of patent 7 years.

To all whom it may concern:

Be it known that I, CHARLES P. MONASH, a citizen of the United States, residing at Chicago, in the county of Cook and State of Illinois, have invented a new, original, and ornamental Design for Support for Statues, of which the following is a specification, reference being had to the accompanying drawing, forming a part thereof.

The figure is a perspective view of a support for a statue, showing my new design.

I claim:

The ornamental design for a support for a statue, as shown.

CHARLES P. MONASH.
